UNITED STATES PATENT OFFICE.

DANIEL M. GRAHAM, OF BOSTON, MASSACHUSETTS.

STOVE OR FURNACE.

SPECIFICATION forming part of Letters Patent No. 268,483, dated December 5, 1882.

Application filed May 15, 1882. (No model.)

To all whom it may concern:

Be it known that I, DANIEL M. GRAHAM, of Boston, in the county of Suffolk, of the State of Massachusetts, have invented a new and useful Improvement in Stoves or Furnaces; and I do hereby declare the same to be described in the following specification and represented in the accompanying drawings, of which—

10 Figure 1 is a vertical section of a stove provided with my invention, the nature of which is defined by the claim hereinafter set forth. Fig. 2 is a vertical section of such stove, showing but one air-induct to its air heating and discharging drum. Fig. 3 is a horizontal section of the stove and its drum.

15 In the drawings, A denotes a common stove or furnace for the combustion of fuel, its grate being shown at a, the ash-chamber at b, the 20 doorway for the supply of fuel at c, and the smoke-discharge flue or pipe at d. Within the upper part of the stove, and above the space for reception of the fuel, is a drum, B, having a series of flue-pipes, e, extending through it 25 from its bottom to its top, and opening through both. Such drum also has made in its bottom a series of educts or holes, f, for the discharge of heated air downward into the fuel or the flame thereof, when such fuel may be in a state 30 of combustion. Into this drum, either at its upper or lower part, is led an air-induction pipe. In Fig. 1 two of such pipes are shown at C and D, one of them—viz., that marked C—being partly outside of the stove and opening 35 into the upper part of the drum. The other pipe or air-induct, after passing into the stove just above its grate, extends upward within the stove to the drum and opens into it at its central part. This latter pipe I provide with 40 a series of holes, g, for the discharge of air from it laterally into the smoke or gas space of the stove. Each air-induct has in it a damper for regulating the flow of air through it, one of such dampers being shown at h and the other 45 at i.

In the above-described stove the smoke and gases escaping from the fuel when in combustion pass around and in contact with the drum and upward through its flue-pipes to the discharge-flue, the drum in the meantime being 50 heated by them, so as to impart heat to the air that may enter it by either or both the induction-pipes. Such air, after having been thus heated, will flow in currents out of the bottom of the drum and upon the fuel or smoke 55 and gases eliminated therefrom, and thereby greatly aid or facilitate combustion of such fuel, smoke, and gases, and consequently improve the heating-powers of the stove.

By having the two air-inducts—one arranged 60 within and the other without the stove, in manner as represented, and each provided with a damper, as set forth—the air can be introduced to great advantage into the drum and stove, and its passage therein can be regulated, as 65 circumstances may require, for obtaining a practically complete combustion of the smoke and gases discharged from the fuel.

From the above it will be seen that in the drum there is no flue extending up through it 70 axially of it, whether for the passage of smoke or air through it, but that it has a series of smoke flues or pipes going through it from top to bottom of it, opening through both, all of which differs from anything shown in either of 75 the United States Patents Nos. 7,164 and 49,652.

I claim—

The combination of the stove and the drum arranged within it, and provided with flue-pipes and air-educts, disposed as set forth, with 80 the two hot-air induction-pipes having dampers, and arranged with such stove and drum substantially as represented.

DANIEL M. GRAHAM.
